SPEED CONTROL DEVICE IN PARTICULAR FOR SPINNING FRAMES

Hans Deutsch, Vienna, Austria

Application March 25, 1952, Serial No. 278,410

10 Claims. (Cl. 74—393)

For operations in the course of which the speed of a machine or apparatus is to be varied simultaneously and automatically in dependence with different, mutually independent laws, speed control devices are known which control either directly the drive unit or a transmission member interposed between the drive unit and the machine. In spinning frames, such speed control devices are called "regulators." In the usual arrangements the motion of an integrating member, being subjected to the combined influences of members for controlling the base and layer speeds, is used to turn a shaft, which adjusts by means of rope pulleys and ropes the brush rockers of the commutator motor driving the spinning frame. Thereby the speed of such motor is varied.

To permit of the setting of the initial spinning speed on a spinning frame as desired in each case, such arrangements provide on the said shaft a coupling which at the same time permits of turning the shaft relative to the integrating member. Such coupling with the associated actuating means is a rather complicated mechanism, which adds to the cost.

This invention relates to an automatic speed control device in particular for spinning frames, which comprises a speed adjusting control member, two camwheels for automatically controlling the speed of a machine according to certain laws, means to rotate said camwheels, a rocker-lever type follower in engagement with each of said camwheels and adapted to receive motion therefrom, a pulling member associated with each follower and operatively connected to said control member, and means selectively to connect each pulling member to its associated follower in any of several positions determining different effective lengths of said follower and thus determining different ratios for the transmission of motion by said follower from its associated camwheel to its associated pulling member.

In the device according to the invention the aforementioned drawbacks of the known regulators are overcome thereby that the adjustment of a certain initial, e. g., initial spinning speed of the machine is enabled without any coupling provided between the integrating member and the rope pulley shaft, at least one of the pulling members being of variable length and both pulling members being connected by the integrating member, directly to the control member.

The speed control device according to the invention is compact and simple and, therefore, inexpensive in construction, and reliable in operation. In conjunction with a speed control gearing, preferably with a friction disk gearing as described, e. g., in the U. S. Patent No. 2,222,281, a preferred embodiment of the invention may be provided which is greatly superior to the known combinations of regulators and commutator motors, particularly as regards cost. Moreover, in conjunction with a particularly small friction disk gearing this embodiment enables the incorporation of automatic control especially in older-type spinning mills with line shaft drive, where the lack of space and considerations relating to the consumption of energy and the arrangement of the drive

2

means virtually preclude the use of the known control devices.

The invention will be explained in more detail with reference to the accompanying drawings.

5 Fig. 1 is a sectional view taken along the line I—I of Fig. 2 through an embodiment shown by way of example of a speed control device according to the invention, combined with a friction disk gearing.

Figs. 2 to 6 show details of the invention,

10 Fig. 2 being a section taken along line II—II of Fig. 1, Fig. 3 a section taken along line III—III of Fig. 1, Fig. 4 a section taken along line IV—IV of Fig. 1, and Fig. 5 a section taken along line V—V of Fig. 1, whereas

15 Fig. 6 is a bottom plan view and a section taken along line VI—VI of Fig. 4.

As may be seen from Fig. 1, the casing 1 accommodates a friction disk gearing 2, known per se, the transmission ratio of which may be varied steplessly by pivotally moving about three triangularly spaced stationary shafts 5 peripheral sets of friction disks 4, engaging a central set of friction disks 3. By a system of two links 7 connecting the two levers 6 for pivotally moving said sets of disks it is ensured that the pivotal movement of the peripheral sets of friction disks 4 takes place symmetrically with respect to the center. Power is transmitted from the central drive shaft 8 through the central set of friction disks 3, the peripheral friction disks 4, the gears 9 connected to the latter, and idlers 10 running on shafts 5, to a gear 11 on the driven shaft 12 coaxial with the driving shaft.

20 The casing 1 further accommodates the speed control device which is combined with the friction disk gearing to form a unit and is accessible by removal of the cover 13. With this unit it is possible to set, and to automatically and steplessly control in the most simple manner the speed, e. g., of a spinning frame connected to the gearing. The cover 13 may be opened pivotally about the axis of a hinge 14 mounted to the casing.

25 40 As usual in spinning frames, the impulses for the base and layer speeds are transmitted to the control device by means of flexible shafts. The rigid ends 15, 16 of said shafts (Figs. 1 and 2) are mounted in the casing and transmit rotation by means of worms 17, 18 and wormwheels 19, 20 to the camwheels 21, 22. The contours of the camwheels conform to speed curves desired during a bobbin cycle and a ringe rail cycle, respectively.

30 45 The aperture 23 in the casing 1 is closed by the cover 24, which has a cylindrical extension 25 protruding into the casing and having bails 26 fixed to its flat portions by means of screws 27, which bails carry the bearings 28 for the shafts 15, 16 and the bearings 29 for the wormwheels 19, 20. The wormwheels 19 and 20 move independently of one another and have interposed between them a joint ball bearing 30. Their turned-off outer journals have splines 31, 32 for mounting the camwheels 21, 22. Pivotally mounted on their outer surfaces the camwheels have slotted pawls 33, 34, which may be moved below headed screws 35, 36 at the end portions of the wormwheels to secure the camwheels against slipping off the wormwheels. This facilitates at the same time the exchange of the camwheels.

40 45 50 55 60 65 70 The followers or rocker levers 40, 41 (Figs. 1 and 3) are pivotally movable about the pin 42 mounted in the casing and carry at their ends freely rotatable rollers 43, 44 rolling along the camwheels 21, 22 to determine different angular positions of the follower levers. As may be recognized from the lever 40 in Fig. 3, the follower levers are of box shape. The roller 43 rotates on balls and is held by a bolt 47 fitted in the parallel side walls 45 of the lever.

The follower levers are engaged by pulling members to transmit the motion of the followers to the control member of the gearing. In the embodiment shown the pulling members consist of roller link chains 48, 49, but ropes or other flexible elements, or rigid elements, such as rods or the like, may also be used. As usual each pulling member engages by means of a keeper pin 50, 51 any one of the numerous notches 52, 53 provided in the upper end faces of the lever walls 45, 46. The effective length of the follower levers may be varied as required by the selection of corresponding notches. 10

Since, in accordance with the invention, the pulling members are of variable length, the last link of each chain has riveted thereto a threaded spindle 54 or 55, on which a knob 56 or 57, provided with a female thread, is adjustable. Each of said knobs engages with a T-shaped carrier 58 or 59 through which the chain 48 or 49, and the spindle 54 or 55, pass freely and which contains keeper pins 50 or 51 on both sides of the spindle in the arms 60 or 61 of its flange. Two further knobs 62, 63 serve as lock nuts to secure the carrier in its adjusted position. Wings 64 or 65 protrude from the flange of the carrier for the keeper pins and are slidingly guided at the inside surfaces of the walls 45 or 46. This precludes any pivotal movement of the keeper pins relative to the followers and ensures a safe engagement in the notches.

Moreover, to eliminate the tendency, particularly of flexible pulling members, to follow an adjustment of the knobs, the lower ends 66, 67 of the threaded spindles, which ends are riveted to the chains, are of U shape. The lateral guide faces of said ends have countersurfaces at the rocker levers or, as shown in Figs. 4 and 6, at the wings 64, 65 of the carriers for the keeper pins.

To set the gearing for a certain initial speed, e. g., initial spinning speed, it is sufficient to make at least one of the two pulling members of variable length. In this case the keeper pins of the other pulling member may be firmly connected to the same, as usual.

The lower ends of each of the chains 48, 49 pass round sprocket wheels 68, 69 and are riveted to a correspondingly formed portion thereof. The two sprocket wheels are pinned on a common shaft 70 to rotate as a unit therewith and are spaced apart a distance equal to the chains and rocker lever spacing. The sprockets and the shaft 70 affixed thereto thus act like a two-armed crank and constitute dual means to integrate motion imparted to the pulling members 48, 49 by the cams 21, 22 and their follower levers 40, 41. The shaft 70 is rotatable in ball bearings 71, 72 of the speed adjusting lever 73 (Fig. 5). This adjusting lever is pivotally movable on one of the stationary shafts 5 of the friction wheel gearing and, carrying one of the peripheral sets of friction disks 4, is connected through links 7 to the levers 6 for pivotally moving the other peripheral sets of friction disks. As a result of this arrangement the motions imparted to the rocker levers 40, 41 by the camwheels 21, 22 are integrated automatically.

To prevent the keeper pins 50, 51 from falling out of the notches 52, 53 of the follower levers, and, where flexible pulling members are used, to maintain the latter in a tense condition all the time, tension devices, such as springs, must be provided. They may be omitted, however, if, in accordance with the invention, the pulling members 48, 49 are linked to the adjusting lever 73 of the friction wheel gearing by means of the shaft 70 of the sprocket wheels 68, 69 so as to oppose the turning moment exercised by the gearing on the adjusting lever, the pulling members being subjected to tension under all conditions of operation of the gearing.

To supervise the setting of the desired speed of the machine, an indicating device is provided, which is separated from the control device by a guard 74 cranked to extend into the casing 1. This guard has a graduated scale provided below a pointer 75 rotatable with one of

the shafts 5 of the gearing. The indication may be observed from the outside through a sight glass 76, which is fixed by means of a frame 78 and screws 79 to the casing, with a packing 77 interposed.

5 The invention is not restricted to the embodiment shown nor by the terms used in describing the same. Within the scope of the claims it covers also other embodiments of speed controls of the type described, including controls following only a single law for the speed curve of the machine. This may be accomplished, e. g., in that one of the rocker levers does not rock because it is associated with a circular disk (camwheel). Finally, one of the rocker levers as well as its associated pulling means may be eliminated altogether.

15 What I claim is:

1. In an automatic speed control device comprising a speed adjusting control member, two camwheels, means to rotate said camwheels, a rocker-lever type follower in engagement with each of said camwheels and adapted to receive motion therefrom, a pulling member associated with each follower, and means selectively to connect a pulling member to a follower in any of several positions determining different effective lengths of said follower and thus determining different ratios for the transmission of motion by said follower from its associated camwheel to said pulling member, an integrating member connected to said pulling members and directly connected to said speed adjusting control member and adapted to integrate motions imparted to said pulling members from said camwheels, at least one of said pulling members being of variable length.

2. In an automatic speed control device comprising a speed adjusting control member, two camwheels, means to rotate said camwheels, a rocker-lever type follower in engagement with each of said camwheels and adapted to receive motion therefrom, a pulling member associated with each follower, a plurality of notches on said followers, a keeper pin member associated with a pulling member and adapted to engage any of the notches on the respective follower to connect said pulling member to said follower in any of several positions determining different effective lengths of said follower and thus determining different ratios for the transmission of motion by said follower from its associated camwheel to said pulling member, an integrating member connected to said pulling members and directly connected to said speed adjusting control member and adapted to integrate motions imparted to said pulling members from said camwheels, and means to adjust the keeper pin members of at least one of said pulling members in the longitudinal direction of the latter and to set them in position, said means comprising a thread provided on the end of said pulling member adjacent to its associated follower and a nut in mesh with said thread and in engagement with said keeper pin member.

3. In an automatic speed control device comprising a speed adjusting control member, two camwheels, means to rotate said camwheels, a rocker-lever type follower in engagement with each of said camwheels and adapted to receive motion therefrom, said followers being of box shape and having parallel side walls, a plurality of notches on said followers, a pulling member associated with each follower, keeper pins associated with each pulling member and adapted to engage any of the notches on the respective follower to connect said pulling member to said follower in any of several positions determining different effective lengths of said follower and thus determining different ratios for the transmission of motion by said follower from its associated camwheel to said pulling member, an integrating member connected to said pulling members and directly connected to said speed adjusting control member and adapted to integrate motions imparted to said pulling members from said camwheels, and means to adjust the keeper pins of at least one pulling member in the longitudinal direction thereof and to

set the same in position, said means comprising a T-shaped carrier having a top flange holding on either side one of said keeper pins, and a wing in engagement with the inside surfaces of the side walls of said follower, a thread provided on the end of said pulling member adjacent to its associated follower, and a nut on said thread and in engagement with the top surface of the flange of said carrier.

4. In an automatic speed control device comprising a speed adjusting control member, two camwheels, means to rotate said camwheels, a rocker-lever type follower in engagement with each of said camwheels and adapted to receive motion therefrom, a plurality of notches on said followers a flexible pulling member associated with each follower, a keeper pin member associated with a pulling member and adapted to engage any of the notches on the respective follower to connect said pulling member to said follower in any of several positions determining different effective lengths of said follower and thus determining different ratios for the transmission of motion by said follower from its associated camwheel to said pulling member, at least one of said pulling members comprising a threaded spindle at its end adjacent to its associated follower, an integrating member connected to said pulling members and directly connected to said speed adjusting control member and adapted to integrate motions imparted to said pulling members from said camwheels, and means to adjust the keeper pin member of said pulling member in the longitudinal direction thereof, said means comprising a nut on said threaded spindle and in engagement with the respective keeper pin member, said threaded spindles having guide surfaces in engagement with surfaces on another part of the device to guide said spindles longitudinally and to prevent rotation thereof upon turning of said nut on said spindle.

5. In an automatic speed control device comprising a speed adjusting control member, two camwheels, means to rotate said camwheels, a rocker-lever type follower in engagement with each of said camwheels and adapted to receive motion therefrom, said followers being of box shape and having parallel side walls, a plurality of notches on said followers, a flexible pulling member associated with each follower, two keeper pins associated with a pulling member and adapted to engage any of the notches on the respective follower to connect said pulling member to said follower in any of several positions determining different effective lengths of said follower and thus determining different ratios for the transmission of motion by said follower from its associated camwheel to said pulling member, at least one of said pulling members comprising a threaded spindle at its end adjacent to its associated follower, an integrating member connected to said pulling members and directly connected to said speed adjusting control member and adapted to integrate motions imparted to said pulling members from said camwheels, and means to adjust the keeper pins of said pulling member in the longitudinal direction thereof and to set them in position, said means comprising a T-shaped carrier having a top flange supporting a keeper pin on either side thereof, and a wing in engagement with the inside surfaces of the side walls of said follower, and a nut on said threaded spindle and in engagement with the top surface of said carrier, said threaded spindle having guide surfaces in engagement with surfaces on said carriers to guide said spindles longitudinally and to prevent rotation thereof upon turning of said nut on said spindle.

6. In an automatic speed control device, which comprises a control member movable to control the speed of a machine, two camwheels, means to rotate said camwheels, a rocker-lever type follower in engagement with each of said camwheels and adapted to receive motion therefrom, a pulling member associated with each follower, and means selectively to connect a pulling member to a follower in any of several positions determin-

ing different effective lengths of said follower and thus determining different ratios for the transmission of motion by said follower from its associated camwheel to said pulling member, at least one of said pulling members being of variable length, and dual integrating means pivotally connected to said control member and having one of said pulling members attached to each part integrating directly and mechanically motions imparted to said pulling members from said camwheels.

7. An automatic speed control device comprising a gearing having a control lever movable to adjust the gearing ratio thereof, two camwheels, means to rotate said camwheels, a rocker-lever type follower in engagement with each of said camwheels and adapted to receive motion therefrom, a pulling member associated with each of said followers, means selectively to connect each of said pulling members to its associated follower in any of several positions determining different effective lengths of said follower and thus determining different ratios for the transmission of motion by said follower from its associated camwheel to said pulling member, at least one of said pulling members being of variable length, and dual integrating means pivotally connected to said control lever and having one of said pulling members attached to each of its two parts, to integrate directly and mechanically motions imparted to said pulling members from said camwheels, said control lever being arranged to receive from the gearing a turning moment and from said pulling members an opposite turning moment to exercise tension on the pulling members throughout its control range.

8. An automatic speed control device as set forth in claim 7, in which said gearing is of the friction disk type.

9. An automatic speed control device comprising a gearing having a control lever movable to adjust the gearing ratio thereof, two camwheels, means to rotate said camwheels, a rocker-lever type follower in engagement with each of said camwheels and adapted to receive motion therefrom, a chain associated with each follower, at least one of said chains being of variable length, means selectively to connect each chain to its associated follower in any of several positions determining different effective lengths of said follower and thus determining different ratios for the transmission of motion by said follower from its associated camwheel to said chain, and an integrating member adapted to integrate directly and mechanically motions imparted to said chains from said camwheels, said integrating member comprising a shaft mounted in said control lever and two sprocket wheels mounted on said shaft to resist relative rotation thereof, each of said sprocket wheels having attached thereto one of said chains, said chains extending in parallel planes.

10. In an automatic speed control device which comprises a speed adjusting control member, a camwheel, means to rotate said camwheel, a rocker-lever type follower in engagement with said camwheel and adapted to receive motion therefrom, a pulling member of variable length associated with said follower and directly connected to said speed adjusting control member, means selectively to connect the pulling member to said follower in any of several positions determining different effective lengths of said follower and thus determining different ratios for the transmission of motion by said follower from said camwheel to said pulling member.
